Filed June 21, 1957, Ser. No. 667,250

6 Claims. (Cl. 37—37)

This invention relates to an excavating machine and more particularly to the conveyor apparatus used to discharge the excavated material from the machine.

For many years it has been customary to provide a trench excavating machine with a discharge conveyor such, for instance, as an endless belt extending across the machine in position to receive and discharge excavated material. Such conveyors have usually been mounted for transverse movement on a suitable support carried by the machine so that they might be extended outwardly from the machine toward either side thereof, as desired, and so control the position of the discharged material. These conveyors have been provided at their opposite ends with drive shafts carrying rollers or drums to drivingly support the endless belt of the conveyor. The belt has been driven by an endless drive chain which has been interconnected between sprocket wheels mounted on the aforementioned drive shafts. A power-driven sprocket wheel has been generally mounted on the support in position to engage one stretch of the chain intermediate the end sprockets and so drive the chain. The drive sprocket wheel has been drivingly connected with the power unit of the excavating machine by generally a reverse gear mechanism which enables the driving of the endless belt in either direction. Generally, the conveyor frame has been provided with a rack coating with a pinion carried by a gear housing mounted on the conveyor support and containing a worm gear reducing unit for shifting the conveyor to either side of the machine. The gear-reducing unit has either been hand-operated as by means of a crank or has been coupled with the motor unit of the excavating machine for power shifting of the discharge conveyor.

The conveyor frame in most prior art arrangements has generally been of arcuate shape in side elevation to provide a facile configuration for shifting the conveyor and for elevating the ends thereof, to discharge the excavated material at variable heights into a receiving vehicle, or onto piles along the sides of the machine. This arcuate construction of conveyor has not always been found satisfactory in that the conveyor is subject to interference and/or damaging contact during digging operations, with exterior obstructions, such as mounds of dirt, rocks, etc. disposed along the rim of the excavation. Moreover, the angle of travel of the belt element of the conveyor has been rather severe at the discharging end thereof when the latter is raised to its maximum height during digging operations. If the radius of the arcuate construction is increased to thereby decrease the angular grade at the ends of the conveyor, an adequate range of vertical height adjustment of the conveyor with respect to the ground level is precluded.

The present invention provides an excavating machine which includes a discharge conveyor which is of generally V-shape in side elevation and which is shiftable

2

to discharge from either side of the machine. The V construction of the conveyor provides greater clearance between the rim of the excavation and the conveyor mechanism, thus aiding to eliminate the possibility of interference between the conveyor and the defining walls of the excavation as well as between the conveyor and other exterior obstructions, and thus precludes damage to the conveyor structure.

Furthermore, the present invention provides a conveyor mechanism in which the angular grade at the discharging end thereof is such that the excavated material may be moved along the conveyor without falling back due to the action of gravity and which provides a greater range of vertical height adjustment of the discharging end of the conveyor as compared to a similar length arcuate type conveyor.

Moreover, the instant invention provides a shiftable conveyor mechanism which is foldable intermediate the ends thereof to maintain the overall width of the machine within predetermined limits during roading operations, and hydraulic means for conveniently accomplishing the shifting and/or folding operations. In addition, the present invention provides various other structural and operational features for the conveyor mechanism that improves the efficiency and usability of the excavating machine.

It is, therefore, an object of the present invention to provide an excavating machine having an unloading conveyor of generally V-shape configuration in side elevation for effective discharge of the excavated material to one or both sides of the machine.

Another object of the invention is to provide an excavating machine of the latter type wherein the unloading conveyor is shiftable by hydraulic means to either side of the machine for selectively increasing or decreasing the height and distance of the discharging end of the conveyor from the dirt-receiving section or station thereof.

Another object of the invention is to provide an excavating machine of the above-mentioned type wherein the conveyor is foldable intermediate the ends thereof for maintaining the overall width of the excavating machine within predetermined limits during roading operations, and wherein hydraulic and linkage means connected to the machine frame and to the conveyor are operable to accomplish the folding and the shifting of the conveyor.

Another object of the invention is to provide an excavating machine of the latter-mentioned type wherein in a novel arrangement of slack take-up sprockets is provided to increase the wrap of the drive chain of the conveyor about the drive sprocket thereof while effectively tensioning the drive chain.

A further object of the invention is to provide a wheel type excavating machine having a transversely extending, shiftable, V-shaped discharge conveyor which is relatively simple and light-weight in construction, comparatively inexpensive to manufacture, and which may be easily folded by means of a single hydraulic piston and cylinder unit to maintain the overall width of the machine within predetermined limits for roading operation, and which utilizes the same hydraulic unit for both shifting and folding of the conveyor.

Other features and advantages of the invention will be apparent from the following description taken in conjunction with the drawings wherein:

Fig. 1 is a side elevation of an excavating machine embodying the present invention;

Fig. 2 is a rear elevation of the machine with certain parts of the machine having been omitted in the interests of simplicity; one operative position of the machine's dis-

charge conveyor and its adjustment or shifting means has been shown in full lines with the remainder of the structure and a second operative position of the conveyor shown in phantom lines, and with the position of the conveyor shifting means in said second operative position being shown diagrammatically in dot-dash lines; also shown in dashed lines is the inoperative folded position of the conveyor and its shifting means;

Fig. 3 is a transverse section illustrating the driving mechanism for the unloading conveyor, the plane of the section being generally indicated by the line 3—3 in Fig. 1;

Fig. 4 is an enlarged fragmentary elevational view taken generally along line 4—4 of Fig. 2 illustrating in detail one of the rollers on the boom of the excavating machine on which the unloading conveyor travels during shifting thereof, and the structure for maintaining the conveyor in assembled relationship on the boom.

Fig. 5 is an enlarged end view of the conveyor taken generally along line 5—5 of Fig. 2 looking in the direction of the arrows;

Fig. 6 is an enlarged fragmentary top plan view taken generally along line 6—6 of Fig. 3 looking in the direction of the arrows and illustrating in detail the latching means for maintaining the hinged sections of the conveyor in operating position;

Fig. 7 is a generally vertical sectional view taken along line 7—7 of Fig. 3.

In the drawings, there is illustrated a wheel-type excavating or ditching machine. As shown in Fig. 1, the machine comprises a frame 10 supported by tractor belts 11. A motor 12 is mounted at one end of the frame and is connected with the tractor belt by a drive chain 13 and a suitable speed reduction gear mechanism (not shown) but arranged to be controlled manually, as for instance, by an operating lever 14.

The excavator wheel is shown at 15 as comprising a pair of rings 16 joined together at their peripheries by U-shaped excavating buckets 17. The excavating wheel is supported by a plurality of rollers 18, one pair of which is supported by a shaft 37, and others of which are shown in Fig. 1, as supported by frame structure 19. The shaft 37 and frame structure 19 are both supported by horizontally extending boom member 20. The inner end of the boom is pivotally connected as at 21 to a carriage 22 which is mounted for vertical movement on mast 24 carried by the forward end of the frame 10.

Cables 26 and 27 secured at one end to winding drums 28 and 29 mounted on the machine frame and at the other end to the outer and inner ends respectively of the boom 20, as at 30 and 31, serve to control the raising and lowering movement of the excavating wheel 15. The drums 28 and 29 are driven by the motor 12 in any suitable manner and are selectively controlled as for instance by operating levers 32 and 33.

The excavating wheel 15 is driven by the motor 12. This wheel carries a series of pins 35 which coact with sprocket wheels 36 (Fig. 1) carried by the shaft 37. Also mounted on the shaft 37 and drivingly connected with the sprocket wheel 36 is a sprocket wheel 38. The latter is drivingly connected as by drive chain 39 with a drive sprocket wheel 40 mounted on a drive shaft 41 carried by the machine frame and drivingly connected with the motor 12 in any suitable manner. The application of power to the shaft 41 is controlled, as by means of a manually operable lever 45.

The drive chain 39 is tensioned by a pair of sprocket wheels 44 carried by a pivoted lever 43 and around which the drive chain 39 is looped. A spring 47 interconnected between lever 43 and the machine frame tensions the driving chain through the medium of the sprockets 44.

The discharge conveyor is generally indicated at 50. This conveyor comprises a segmental frame 51, mounted for movement transversely of the frame 10 and boom structure 20 of the machine.

In the embodiment of the invention shown, frame 51 comprises two sections 51a and 51b, hinged together as at 52. Each of sections 51a and 51b comprises a pair of longitudinally spaced, elongated rail members 53 connected by cross bar members 54 (Figs. 6 and 7). Preferably fabricated, side wall structure 53a projects upwardly from each of rail members 53 and is suitably attached thereto. A transversely extending shaft 55 is mounted on each end of the conveyor and carries a belt-supporting drum 56. Since the V-shaped construction of the conveyor provides greater clearance between the conveyor frame and the rim of the excavation, drum 56 may be of larger than usual size, thus providing more positive driving characteristics for the conveyor. Auxiliary belt supporting rollers 56a are disposed intermediate the ends of the belt as best shown in Figs. 2 and 3. The rollers 56a are rotatably mounted on shafts carried by conveyor frame 51. Material is retained on the conveyor by elongated side plate members 58 in combination with side wall structure 53a. Plates 58 extend over the top reach of the conveyor belt 59 and are supported on one side of the conveyor frame by side brackets 60. Plates 58 on the other side of the conveyor frame are supported on an extension of the associated side wall structure 53a, as may be best seen in Fig. 7.

Section 51b of the conveyor frame on its inner end embodies the base portion 61 of the V construction. Base portion 61 is of generally V-shape, in side elevation, fabricated construction, and is rigidly connected at one end to section 51b of the conveyor frame and at its other end is hinged, as aforementioned, at 52 to section 51a of the conveyor frame. It will be seen, therefore, that the unloading conveyor in effect comprises a pair of outer, generally linearly extending sections which diverge outwardly with respect to one another and a central portion or section of generally angular or arcuate-like configuration, in side elevation, which is attached to the outer sections to form the V-shaped contour of the conveyor. It has been found that the most desirable angle of grade or elevation at the discharging end of the conveyor, when it is raised to its maximum height, should be approximately 30 degrees with respect to the horizontal, in order to obtain an adequate range of vertical height adjustment of the discharging end with respect to ground level, while still permitting the excavated material being carried by belt element 59 to be moved upwardly without slipping back on the conveyor due to the action of gravity. The V-shaped configuration of the conveyor provides for a greater adjustment of the discharging end of the conveyor, with a smaller amount of lateral or shifting movement, as compared to an arcuate type conveyor of corresponding length, as will be understood by those skilled in the art. It will be seen that lateral or transverse movement of the conveyor provides a wide scope of vertical height positions of the discharging end of the conveyor, ranging from a substantially horizontal position to the diagonally extending position of the outer end of the conveyor section 51a illustrated in Fig. 3 of the drawings.

Latch structure 62 (Fig. 6) maintains the sections 51a and 51b of the conveyor frame in normal operating position. Latch structure 62 comprises a tongue element 62a attached at one end to angular portion 61 on conveyor section 51b and a pair of transversely spaced flanges 62b attached to section 51a of the conveyor frame between which tongue element 62a is receivable. Aligned openings 63 in elements 62a and 62b are adapted to receive therethrough a removable retaining element 64, such as a pin or bolt, for holding the conveyor sections 51a and 51b in operating position.

As shown in Figs. 2 and 3, the boom 20 comprises a pair of spaced members 65, which in the embodiment illustrated are of polygonal configuration in vertical cross section, and are connected by cross-frame elements 65a (Fig. 3). Each of beams 65 carries a pair of spaced brackets 66 (Figs. 3 and 4) on the inner side surface

thereof. A conveyor supporting roller 67 is journaled on each of the brackets and engages the underside of the conveyor frame 51 to support and guide the latter.

Referring in particular to Fig. 4 which illustrates in detail the supporting roller and bracket structure 67 and 66, it will be seen that each of rails 53 has attached thereto, on the underside thereof, an elongated plate member 68 which engages the associated roller 67 to support the conveyor frame on boom 20. A lug or pin 69 secured to the upper end of the bracket 66 overlies one end of plate 68 and serves to retain the conveyor seated on the roller 67.

The conveyor 50 is driven from the shaft 37 which, as heretofore described, is driven by the motor 12. As illustrated in Fig. 1, the shaft 37 is provided with a sprocket wheel 70 which is drivingly connected as by a drive chain 70a with a sprocket wheel 71 carried by a shaft 71a journaled in a housing 72 secured to boom 20. The housing 72 is provided with a power transmission unit, including a reverse gear mechanism for reversing the direction of drive of conveyor 50. A drive shaft 74 which is operatively connected to the power transmission unit and reverse gear mechanism extends exteriorly of housing 72 and is provided with a drive sprocket wheel 74a (Figs. 1 and 3), which is connected with the conveyor shafts 55 heretofore mentioned by an endless drive chain 75 (Fig. 3). Drive chain 75 is looped about the drive sprocket wheel 74a and a pair of sprocket wheels 76 which are secured to conveyor shafts 55. A pair of idler sprocket wheels 77 carried by a cross-member 65a of the boom 20 serve to guide the lower reach of the drive chain 75 above the beams 65 of the boom. An idler sprocket wheel 77a mounted on central portion 61 of the conveyor frame 51 maintains the upper stretch of chain 75 below the upper extremity of the conveyor 50 and out of damaging contact with the excavating wheel 15.

The drive chain 75 is tensioned by a pair of idler sprocket wheels 78 and 79. In Fig. 3 of the drawings, all of the aforementioned sprocket wheels are only diagrammatically illustrated. Sprocket wheels 78 and 79 are rotatably mounted on depending arm elements 78a and 79a, respectively, which are pivoted as at 78b and 79b on their upper ends to boom structure 20. An adjustable spring unit 80 is connected between sprocket arm 78a and 79a and is connected thereto intermediate the ends thereof. A nut 80a threaded on shank 80b of unit 80 provides means for varying the tension in spring 80c. Unit 80 tends to pull arms 78a and 79a together, thereby taking up the slack in the drive chain. In this connection, assuming that the drive sprocket 74a is moving in the direction of the arrow, the tight section 81 of the lower stretch of drive chain 75 will cause take-up sprocket 78 to pivot away from drive sprocket 74a, thereby pulling take-up sprocket 79 toward the drive sprocket 74a through the medium of spring unit 80. Sprocket 79 thereby takes up the slack in the loose section 82 of the lower stretch of drive chain 75 and results in greater chain wrap around drive sprocket 74a. A greater length of drive chain is necessary for a predetermined length of conveyor of the V-shaped type of the invention as compared to the arcuate type, due to the greater range of vertical movement of the conveyor upon transverse movement thereof. Accordingly, more slack results in the drive chain. The latter slack take-up arrangement provides a much more efficient and positive driving mechanism, thereby reducing the possibility of slippage and the chance of failure of the drive chain and drive sprocket members.

The lower stretch of the endless belt element 59 passes beneath boom structure 20 as best shown in Fig. 3. Rollers 84 rotatably mounted on boom structure 20 serve to guide the lower reach of belt 59 below the beams 65 of the boom.

A hydraulic motor unit could be used to drive the belt element of the conveyor instead of the mechanical gear, chain and sprocket arrangement illustrated. Such a hy-

draulic motor could, for instance, be mounted on either end of the conveyor frame in driving relationship with one or both of belt supporting drums 56, and would be suitably connected to a source of pressurized fluid such as a pump mounted on the machine chassis. The aforementioned advantages of the V-type conveyor of the instant invention would exist equally well with such a hydraulically driven conveyor as compared to the mechanically driven arrangement shown.

10 Shifting of the conveyor 50 to either side of the excavating machine is accomplished by means of double acting hydraulic unit 86 (Fig. 2) in combination with linkage structure 87. One end of hydraulic unit 86 is pivotally mounted by means of bracket 88 (Fig. 1) on 15 boom 20 while the other end of unit 86 is pivotally connected to link rocker arm 89. The outer end of arm 89 is pivotally attached as at 90, as by means of removable pin 90a (Fig. 5) to lug element 92 which, in turn, is connected to side wall structure 53a on the outer end 20 of conveyor frame 51.

The inner end of link arm 89 is pivotally connected as at 94 to the outer end of link arm 96. The inner end of arm 96 is pivotally mounted as at 97 (Fig. 1) to boom structure 20 of the machine. Hydraulic unit 86 is connected to a source of pressurized fluid such as a pump (not shown), but which may be of a conventional type, mounted on the machine chassis. Feed lines 98 (Fig. 2) connect unit 86 to the source of pressurized fluid and suitable valve means (not shown) which may be of any 25 conventional character, control the flow of fluid to unit 86 to actuate the latter. When the conveyor is in a laterally disposed position on either side of the machine chassis, all of the stress due to the weight of hinged sections 51a and 51b of the conveyor is transmitted directly to the 30 aforementioned latch structure 62 locking the conveyor sections together, none being absorbed by the linkage 87 and hydraulic unit 86.

When it is desired to shift the conveyor from the position shown in Fig. 2 to the other side of the machine or 40 to any intermediate position, the aforementioned valve means is actuated, thereby supplying pressurized fluid to the cylinder of hydraulic unit 86 and causing the plunger portion to retract. Upon inward movement of the 45 plunger, the linkage structure 87 is caused to fold inwardly thus shifting the conveyor laterally. The conveyor is thus moved transversely on the aforementioned rollers 67 on beam members 65 to the desired position with respect to the machine chassis and the bottom structure 20. In Fig. 2, the location of the end of the conveyor when it is moved transversely to its maximum 50 lateral position on the other side of the machine chassis, is shown in phantom lines as at 100. The resultant folded position of actuating linkage 87 and associated hydraulic unit 86 is also shown in dot-dash. Lugs 102 (Figs. 3 55 and 7) attached to the underside of plates 68 on rail members 53 and adapted for engagement with boom structure 20 may be provided to limit the transverse shifting movement of the conveyor.

When it is desired to fold the conveyor to maintain 60 the width of the excavating machine within predetermined limits for roading, the aforementioned pin 64 is removed from latch structure 62 on each side of the conveyor frame, and the weight of section 51a of the conveyor in combination with actuation of the plunger element of 65 hydraulic unit 86 causes the conveyor section 51a to fold down about its hinged connection 52 to substantially the position shown in dashed lines and indicated by reference number 103 in Fig. 2 of the drawings.

Pin 90a may then be removed to disconnect the end 70 of linkage arm 89 from the conveyor after which the hydraulic unit 86 may be further retracted to fold linkage 87 within the general outline of the excavating machine, thus providing a machine of predetermined width for 75 roading operations. During the folding operation of the

conveyor a spring actuated latch mechanism generally indicated at 104, attached to boom structure 20 and adapted to coat with the underside of the conveyor frame may be provided to hold the conveyor against lateral movement. Such a latch mechanism is shown and described in United States Patent No. 2,598,339, issued May 27, 1952, to Albert R. Askue, and accordingly will not be discussed in detail here.

From the foregoing description and accompanying drawings, it will be seen that the invention provides an excavating machine having a transversely shiftable, unloading conveyor mechanism which is of generally V-shaped configuration in side elevation and providing a lesser angle of grade or elevation at the discharging end of the conveyor for efficient movement of the excavated material along the conveyor and one which provides a greater clearance between the conveyor frame and the rim of the excavation, as well as providing a greater range of vertical height adjustment for the discharging end of the conveyor. Moreover, the invention provides an excavating machine of the latter-mentioned type, wherein the discharge conveyor is shifted transversely of the chassis of the excavating machine by means of a hydraulic unit in combination with a linkage mechanism, and wherein a novel arrangement is provided for taking up the slack in the drive chain of the conveyor. In addition, the invention provides a discharge conveyor which is foldable intermediate the ends thereof, thus permitting the use of a greater length conveyor during digging operations which results in a greater lateral range of discharge of the excavated material, but providing means for maintaining the overall width of the excavating machine within predetermined limits for roading operations.

The terms and expressions which have been employed are used as terms of description and not of limitation, and there is no intention in the use of such terms and expressions of excluding any equivalents of the features shown and described or portions thereof, but it is recognized that various modifications are possible within the scope of the invention claimed.

I claim:

1. A discharge mechanism for an excavating machine or the like comprising a support, a discharge conveyor mounted on said support, said conveyor including a frame of generally V-shaped configuration in side elevation, means mounting said frame on said support for anti-friction movement of said frame transversely of said support, a reciprocable hydraulic motor unit pivotally mounted at one end adjacent an outer edge portion of said support, collapsible linkage mechanism pivotally connected at one end to said outer edge portion of said support and at the other end being pivotally connected to the respective end of said frame, the other end of said hydraulic motor unit being pivotally connected to said linkage mechanism for actuating the latter and thus shifting said conveyor transversely on said support whereby a rocking of said conveyor on said support occurs to locate the rectilinear end portions of said conveyor in selective angular relationship with respect to the horizontal, said conveyor including spaced belt-supporting means mounted on said frame, an endless belt looped about said means and having its upper stretch position to receive material to be discharged, a sprocket wheel drivingly connected to each of said belt-supporting means, a drive sprocket wheel mounted on said support, an endless drive chain interconnecting said first-named sprocket wheels and said drive sprocket wheel and having its bottom stretch engaged by said drive sprocket wheel, chain tensioning means mounted on said support on opposite sides of said drive sprocket wheel and coacting with said drive chain to take up slack in the latter, said tensioning means comprising spaced sprocket wheels, each of said last-mentioned wheels being rotatably mounted on a depending arm member, said arm member being pivotally mounted at one end thereof to said support

and a resilient unit extending between said arm members and being connected thereto for drawing said last-mentioned sprocket wheels toward one another into engagement with said drive chain, said last-mentioned wheels being operative to increase the wrap of said drive chain about said drive sprocket, and means for adjusting the tension in said resilient unit.

2. In an excavating machine including a chassis, an excavating unit, a support for said unit, a discharge conveyor including a frame mounted for lateral shifting movement on said support, said conveyor being movable to either side of said machine to extend outwardly of the chassis of the machine and being adapted to receive and discharge excavated material from said unit, means to lock said conveyor on said support to prevent transverse movement thereof, said frame comprising a plurality of hinged sections, manually releasable latch means for maintaining said sections in normal operative position, said sections when in said last-mentioned position defining in side elevation a generally V-shaped structure, a linkage device mounted on said support, means to pivotally connect said linkage device to one end of said frame, a hydraulic piston and cylinder unit mounted on said support and pivotally connected to said linkage device, means to supply pressurized fluid to said hydraulic unit to activate the latter whereby said linkage device shifts said conveyor transversely of said machine, at least one of said sections being foldable with respect to the other of said sections, whereby said conveyor is disposed within the outline of the chassis of said machine upon locking of said first-mentioned means, unlocking of said second-mentioned means and actuation of said hydraulic unit.

3. In an excavating machine in accordance with claim 2, wherein said third-mentioned means comprises a removable holding member and said linkage device extends outwardly of the outline of the chassis of said machine, said linkage device being foldable within the outline of the chassis of said machine upon removal of said holding member.

4. In an excavating machine, in accordance with claim 2, wherein said linkage device comprises an inner arm member hinged at one end to an outer arm member, the outer end of said last-mentioned member being pivotally connected to said frame, the inner end of said first-mentioned arm being pivotally connected to said support, and the outer end of said hydraulic unit being pivotally connected to said outer arm member intermediate the ends thereof.

5. In an excavating machine, an excavating unit, a support for said excavating unit, a discharge conveyor including a frame mounted for lateral shifting movement on said support, said conveyor being shiftable on said support to an operative position wherein the conveyor extends laterally beyond the general outline of said machine, said conveyor being adapted to receive thereon and discharge therefrom excavated material from said excavating unit, said frame comprising a plurality of hinged sections, releasable latch means for maintaining said sections in normal operative relation, conveyor shifting means including a fluid powered motor unit coacting between said support and an end of said frame for shifting said conveyor transversely of said support, at least one of said sections being foldable relative to the other of said sections and to a position wherein the conveyor is disposed substantially inwardly of the general outline of said machine upon release of said latch means and actuation of said motor unit.

6. In an excavating machine in accordance with claim 5 wherein said frame is of generally V-shaped configuration in side elevation when in normal operative condition, said shifting means including an articulated linkage device pivotally mounted at one end of said support and pivotally connected at the other end to said frame, said motor unit comprising a double-acting reciprocal hy-

draulic piston and cylinder unit pivotally mounted at one end on said support and pivotally connected at the other end to said linkage device.
